UNITED STATES PATENT OFFICE.

THOMAS NATHAN RUSSELL, OF CHICAGO, ILLINOIS, ASSIGNOR TO CHICAGO-CLEVELAND CAR ROOFING CO., OF CHICAGO, ILLINOIS, A CORPORATION OF ILLINOIS.

CAR-ROOF.

1,291,171.

Specification of Letters Patent. Patented Jan. 14, 1919.

Application filed August 12, 1915. Serial No. 45,225.

To all whom it may concern:

Be it known that I, THOMAS N. RUSSELL, a citizen of the United States, residing in Chicago, in the county of Cook and State 5 of Illinois, have invented a new and useful Improvement in Car-Roofs, of which the following is a specification.

The invention relates to outside car roofs, and more particularly to such roofs having a 10 roof lining or insulation applied at the under sides of the roof sheets. Under some climatic conditions and extremes of temperature change, and particular character of the load within the car, moisture within 15 the car condenses and collects upon the under sides of the metallic roof sheets. This condition is commonly called sweating, and it is the object of the present improvement to prevent such condition under any circumstances. The invention also relates to 20 the roof frame with which such insulation is combined, and to other details of construction; and to all new features of advantage which are, broadly or specifically, inherent 25 in my improved roof.

The invention consists in the parts, and combinations thereof, hereinafter set forth and claimed.

In order to make the invention more 30 clearly understood there are shown in the accompanying drawings means for carrying the same into practical effect without limiting the improvements, in their useful applications, to the particular construction which, 35 for the purpose of example, has been illustrated. In said drawings—

Figure 1 is a plan view of a portion of a car roof embodying the invention, certain of the parts being broken away to better illustrate the construction.

Fig. 2 is a side view of the same.

Fig. 3 is a vertical cross section of a portion of the roof, on a larger scale.

Fig. 4 is a similar section of the eaves 45 portion of the roof, on a still larger scale.

Fig. 5 is a vertical section taken longitudinally of the car, of the carline and contiguous parts.

Fig. 6 is a vertical sectional view, on a 50 larger scale, of one of the roof sheet securing bolts.

Fig. 7 is a plan view of the same.

Fig. 8 is a plan view of the washer which is in some cases used with the said bolt.

Fig. 9 is a cross section of the same.

Fig. 10 is a vertical section, taken at the ridge of the car and longitudinally of the latter.

Fig. 11 is a similar view taken transversely of the car.

Fig. 12 is a plan view of one of the intermediate roof sheets.

Fig. 13 is a plan view of one of the end roof sheets.

Fig. 14 is a plan view of one of the car- 65 lines.

Fig. 15 is a side view of the same.

Fig. 16 is a vertical sectional view of the end portion of the car, taken at the ridge of the car and longitudinally of the latter. 70

Fig. 17 is a vertical sectional view of one of the end roof sheets.

Fig. 18 is a similar view of the other end roof sheet.

Fig. 19 is a similar view of one of the 75 intermediate roof sheets.

In Figs. 17, 18 and 19 the plane of the section is vertical and longitudinal of the car, and the middle portions of the sheets are broken away.

Referring to the drawings, the upper part of the car body frame constitutes the roof frame; and it comprises side plates which are or may be of what is known as Z cross section, having a vertical web 1, an inwardly 80 extending top flange 2 and an outwardly extending bottom flange 3. The side plates are united at the ends of the frame by end plates 4 which may be arched to conform to the roof. The above described roof frame

members are carried by posts or stakes and braces of known construction. 5 is the side sheathing and 6 the end sheathing. 7 indicates the carlines arranged at suitable intervals along and resting on the top flanges 2 85 of the side plates, to which the lateral flanges 8 of the carlines are bolted or riveted as shown at 9. The carlines are arched from side to side of the car, and their middle portions between the flanges 8 are channel bars

of inverted U-shape, having vertical side flanges 10 and a top connecting web 11. At suitable points, in the illustration shown as four points, the web 11 is perforated with 90

bolt holes 12 to receive the roof sheet securing bolts 13. The ends of the carlines terminate at or about the planes of the webs 1. The carline is or may be die-formed of one

piece of heavy sheet metal pressed into the form shown.

The roof sheets are shown at 14, and are or may be die-formed of medium heavy 5 sheet-metal so as to have the forms shown. They are arched across the ridge from eaves to eaves of the roof, conforming substantially to the arches of the carlines. The main portions of the roof sheets rest on 10 filler bars above the bottom side flanges 8 of the carlines. The side edges of the roof sheets, transversely of the car, are formed to conform substantially with and to inclose the upper central parts of the carlines, that 15 is to say the inverted U-channels thereof, having vertical flanges 15 which fit against the side flanges 10 of the carlines and top flanges 16 which fit over the webs 11. Each intermediate roof sheet terminates at one 20 side in the said flange 16, and at its other side the flange 16 is continued downward in the form of a flange 17 which extends to the surface of the roof and terminates in a short outward flange 18. The last described 25 edge of the sheet constitutes a seam cap which incloses the carline and also the flange 15 and terminating flange 16 of the next contiguous sheet. The intermediate sheets are best seen in Figs. 12 and 19. Each end sheet 30 is formed with a depending flange 19 (Figs. 17 and 18) which fits over the end fascia 20 (Fig. 16). One end sheet has a seam cap formation 15, 16, 17, 18 at its inner edge (Fig. 17), and the other end sheet is formed 35 with the terminal flange 16 (Fig. 18) to fit within such a seam cap.

In order to insure against leakage through the bolt holes 12 I have devised an improved roof sheet securing bolt adapted to 40 the carline and roof sheet structure above described. The holes 12' in the flanges 16 are surrounded by upwardly extending marginal flanges 21 (Figs. 17, 19) which are bent up from the flange 16. 22 is a washer 45 of special form (Figs. 8 and 9) which is formed on its under side to conform to the tops of the carlines and flanges 16, being of saddle form with depending side flanges 23 which embrace the outermost cap flange 16. 50 It has a central hole 24 for the bolt 13, which hole conforms to the flanges 21 and is bounded by upwardly extending flanges 25 which inclose said flanges 21 (Fig. 5). The bolt 13 extends down through said 55 washers, flanges 16 of the roof sheets and webs 11 of the carlines, and is secured by a nut 26 arranged between the sides 10 of the carlines. Nut locks 27 of suitable character are or may be applied to said nuts. The 60 head of the bolt is formed with a thin bendable edge 28 (Fig. 7) for inclosing the said flanges 25 of the washers. This edge 28, is, before or after the insertion of the bolt, swaged down to form a downwardly extending flange 29 (Fig. 6), which closely em-

braces the washer flanges. Any dashing or leakage of water through the holes 12 is thus prevented.

The sweating of the under sides of the roof sheets, which does not dry off quickly 70 as on the tops of the sheets and which causes rusting and deterioration of the roof sheets, is entirely prevented under all conditions by the insulation material 30. This insulation is or may be of wood in the form of tongued and grooved boards about one half an inch thick, which are inserted into the space between the carlines and at the under sides of the roof sheets. The said roof frame comprises longitudinal members, such as a ridge 80 pole 31 and purlins 32, which are arranged under the carlines and supported thereby. These members are preferably channel irons of inverted U-shaped cross section (Fig. 3) having lateral flanges 33 which are riveted 85 to the carline flanges 8. Within the channels of said members are seated filler bars 34 extending from carline to carline and extending up to and supporting the insulation material 30. The ends of the latter rest on the 90 flanges 2 of the side plates in the angles between the same and the roof sheets (Fig. 4).

The boards forming the insulation can be inserted into place in a direction longitudinal of the car and fitted together before or 95 as the roof sheets are laid and secured.

Two of the roof sheet fastenings, by the bolts 13, are preferably arranged to be under the saddle 35 for the running boards 36. In such case the said saddle is secured on the carline by the bolts 13 and forms a substitute 100 for the washers 22, and the holes in the saddle for said bolts are surrounded by upwardly extending flanges 37 (Fig. 10), which are inclosed by the bolt head flanges 105 29, as already described in the case of the washer flanges 25. The edge of the saddle is formed with a downwardly extending flange 38 which partly embraces the roof sheet cap over the carline.

The flanges 15, 16, 17 and 18 of the roof sheets are preferably continued over the outer edge of the side plates (Fig. 4) and down on the outer sides of the webs 1. Here they contain filler castings 39, and are secured by bolts 40 which pass through the flanges 16, the filler castings and the side plates. The corresponding depending eaves flanges 41 of the bodies of the roof sheets are secured at their middles to the side plates 110 120 by bolts 42.

What is claimed is:—

1. In a car roof, in combination: carlines; roof sheets extending over the carlines and perforated with bolt holes formed with upwardly extending marginal flanges; washers having upwardly extending flanges inclosing the flanges on the roof sheets; and bolts extending down through said washers, roof sheets and carlines, the heads of said bolts 125 130

being formed with downwardly extending flanges inclosing the said flanges on the washers.

2. In a car roof, in combination: inverted U-shaped carlines; roof sheets extending over the carlines, formed with bends inclosing the upper parts of the carlines, and perforated with bolt holes formed with upwardly extending marginal flanges; washers having upwardly extending flanges inclosing the flanges on the roof sheets; bolts extending down through said washers, roof sheets and top webs of the carlines, the heads of said bolts being formed with downwardly extending flanges inclosing the said flanges on the washers; and nuts on said bolts between the sides of the carlines.

3. In a car roof, in combination: carlines; roof sheets extending over the carlines and perforated with bolt holes formed with upwardly extending marginal flanges; washers having upwardly extending flanges inclosing the flanges on the roof sheets; and bolts ex-

tending down through said washers, roof sheets and carlines, the heads of said bolts 25 being formed with thin bendable edges for inclosing the said flanges on the washers.

4. In a car roof, in combination: carlines; roof sheets extending over the carlines and perforated with bolt holes formed with upwardly extending marginal flanges; a running board saddle, perforated and formed with upwardly extending flanges which surround said marginal flanges; and bolts extending down through said saddle, roof 30 sheets and carlines, the heads of said bolts being formed with downwardly extending flanges inclosing the said flanges on the saddle.

In testimony whereof, I have hereunto set 40 my hand in the presence of two subscribing witnesses.

THOMAS NATHAN RUSSELL.
